IMPACT-TYPE MARKING DEVICE

Evan S. Nelson and Charles J. Nelson, Iron Mountain, Mich., assignors to The Nelson Company, Iron Mountain, Mich., a firm

Filed Dec. 2, 1955, Ser. No. 550,664

7 Claims. (Cl. 15—131)

This invention relates to marking devices and particularly to an improved impact-type marking device.

The invention is described as embodied in a "paint hammer" which includes a can of paint with an outlet neck of reduced diameter and a special protruding cushion applicator fastened to the neck of the can. The can is releasably secured to a handle and is intended to be used in most instances by striking it "hammer" fashion against the surface to be marked.

Such a "paint hammer," for example, can be used for marking trees, stacks of lumber, railroad ties, and many other articles where coded information may be recorded as a function of color or the number or arrangement of marks.

The various aspects, features, and advantages of the invention will be pointed out in or be apparent from the following detailed description of a marking device incorporating the invention considered in connection with the accompanying drawings, in which:

Figure 1 is a perspective view of a "paint hammer" incorporating the invention; and

Figure 2 is an exploded perspective view of the applicator forming part of the device shown in Figure 1.

As shown in Figure 1, the "paint hammer" includes a handle 2, for example about two feet long, arranged to support a container 4 which may be filled with paint or some other marking fluid. A somewhat pervious protruding cushion applicator 6 is secured to one end of the container 4.

In use the "paint hammer" is held by the handle 2 and the applicator 6 is caused to strike the article to be marked. This action forces a small quantity of paint from the can 4 to penetrate the pervious applicator 6 and be applied to the article struck with the applicator.

The can 4 can be formed of a standard screw-cap paint can or other conventional container. As best shown in Figure 2 the applicator is formed of a perforated screw-type cap 8 which is covered by suitable porous material that permits the transmission of controlled amounts of paint and at the same time provides a cushion for absorbing part of the impact when the article to be marked is struck.

Preferably the perforations 10 in the cap 8 are made by driving sharp-pointed punches against the inner surface of the cap so as to form outwardly extending barbs. The cushion, in the example, is formed by placing three pieces 14, 16, and 18 of jute fabric, such as heavy burlap, of increasingly larger diameter over the perforations and barbs and securing these cushioning members by a cover 20 of mesh material made of loosely-knitted, heavy cotton thread or other suitable material. The cover mesh 20 is secured to the neck of the container 4 by any suitable type of clamp formed in this example by a wire loop 22 in which the ends of the wire are twisted together to anchor the porous cover 20 firmly in position and prevent leakage around the edges of the cover.

The cushioned structure of the pervious opening in the container permits the paint to be driven by impact

2

through the fabric without damage to the surface being marked or to the paint container.

In order to protect the contents of the can 4 during shipping, a cap 24 of foil or other flexible impervious material is placed over the cover 20 and secured in position by a plastic band 26. Thus, it is only necessary to remove the band 26 and cap 24 to place the container in condition for use.

The container 4 is mounted in a bracket 28 comprising an open-work socket providing a cylindrical receptacle for receiving the container 4. This receptacle engages the sides and end of the container and could be fully closed on the bottom and sides as desired. The bracket 28 is secured to yoke members 30 of the handle 2 and includes a pair of resilient straps extending along the sides of the container with an inward hook releasably securing the container in place. The container 4 thus may be positioned with its longitudinal axis substantially at right angles to the handle 2, or it may be positioned at any other desired angle. Once the position is selected it can be locked in position by means of wing nuts 32 on diametrically opposite sides of the cylindrical receptacle.

What is claimed is:

25 1. An impact type marking device comprising a container for marking liquid, a screw-type perforated lid on the container, a plurality of layers of pervious fabric positioned one on top of the other over said perforations, successive ones of said layers being of gradually increasing diameter, and means holding said successively larger layers of fabric on said perforated lid forming a rounded cushion, said successively larger layers of fabric providing a cushion for absorbing impact while transmitting controlled amounts of marking liquid therethrough.

2. An impact type marking device comprising a container for marking liquid having a perforated screw-type cover of substantially smaller diameter than the diameter of said container, three pieces of jute positioned over said cover and being of successively increasing diameter, the smallest diameter being adjacent said perforations, a mesh fabric positioned over said jute and being drawn back tightly around the jute pieces and around the outer surface of said cover for shaping said pieces of jute into a convex cushion on top of said perforated cover, and means securing said mesh fabric to said cover, said pieces of jute and mesh fabric providing a cushion for absorbing impact when struck against an article to be marked and transmitting controlled amounts of marking liquid therethrough.

3. An impact type marking device comprising a container for marking liquid having a perforated screw-type cover, a plurality of pieces of jute positioned over said cover and being of successively increasing diameter, the smallest diameter being adjacent said perforations, a mesh fabric positioned over said jute and being drawn back snugly around the outer surface of said cover for holding said pieces of jute in a rounded pad, means securing said mesh fabric to said cover, and a handle extending at an angle from said container.

4. A ready-to-use impact type paint marking device including a container for paint having a perforated screw-type cover of substantially smaller diameter than the diameter of said container, a plurality of pervious resilient layers of successively larger diameter over said cover forming a convex cushion adapted to transmit paint therethrough, a mesh overlying said convex cushion and the sides of said cover, a loop around the sides of said cover overlying said mesh and securing said mesh in place on the cover, and a cap of flexible impervious material overlying said mesh and removably secured in place.

5. An impact-type marking hammer for marking ob-

jects with paint and similar marking fluids by striking the objects to be marked in hammer fashion, said paint hammer comprising a handle adapted to be held in the hand and swung in hammer fashion, a bracket secured to said handle, a container for paint and similar marking fluids held in said bracket, said bracket including socket means engaging the sides and one end of said container and including a resilient strap extending along the side of the container with an inward hook releasably engaging the opposite end of the container for holding the container in place in the bracket, said container and bracket effectively forming the head of said hammer, said container having a protruding neck of reduced diameter at said opposite end thereof, and an impact cushion and applicator for the marking fluid on the neck of the container comprising a pervious cushion protruding forwardly beyond the neck of the container.

6. An impact-type marking hammer for marking objects with marking fluids by striking the objects to be marked in hammer fashion, said marking hammer comprising a handle adapted to be held in the hand and swung in hammer fashion, a yoke secured to one end of said handle, a bracket including a cylindrical receptacle adapted to hold a cylindrical container therein, means adjustably securing said bracket to said yoke for adjusting the angle of said bracket with respect to the handle, a cylindrical container for the marking fluid releasably held in said bracket with said cylindrical receptacle engaging the side and one end of said container, said bracket including resilient strap means extending from said cylindrical receptacle and releasably hooking the opposite end of said container, said container and bracket effectively forming the head of said hammer, said cylindrical container having a neck of reduced diameter at said opposite end thereof, and an impact cushion

and applicator for the marking fluid protruding beyond the neck of the container comprising a perforated member extending across the neck of the container and a pad of pervious material over said perforated member and protruding forwardly.

7. An impact-type marking hammer as claimed in claim 6 and wherein said means adjustably securing said bracket to said yoke are positioned at points on diametrically opposite sides of said container near the open end of said cylindrical receptacle, said resilient strap means extending from said receptacle at said points.
